(57) **CLAIM**

The ornamental design for a lid for drinking bottle, as shown and described.

DESCRIPTION

FIG. 1 is a top view of the lid for drinking bottle.

FIG. 2 is a bottom view of the lid for drinking bottle.

FIG. 3 is a front view of the lid for drinking bottle.

FIG. 4 is a rear view of the lid for drinking bottle.

FIG. 5 is a right side view of the lid for drinking bottle, the left side being a mirror image thereof.

FIG. 6 is a front, top, right side perspective of the lid for drinking bottle.

FIG. 7 is a rear, bottom, right side perspective of the lid for drinking bottle; and,

FIG. 8 is a front, top, right side perspective of the lid for drinking bottle in the open position.

The portions of the lid for drinking bottle shown in broken lines form no part of the claimed design.
